UNITED STATES PATENT OFFICE.

CHARLES F. BUENTE, OF AVALON, PENNSYLVANIA.

COLLAPSIBLE CORE FOR MOLDS.

1,312,157.

Specification of Letters Patent.

Patented Aug. 5, 1919.

Application filed October 2, 1917. Serial No. 194,389.

To all whom it may concern:

Be it known that I, CHARLES F. BUENTE, a citizen of the United States, residing at Avalon, Allegheny county, Pennsylvania, 5 have invented an new and useful Improvement in Collapsible Cores for Molds, of which the following is a full, clear, and exact description, reference being had to the accompanying drawings, forming part of 10 this specification, in which:

Figure 1 is a vertical section through one form of my improved core.

Fig. 2 is a horizontal section of a portion of the core shown in Fig. 1.

Fig. 3 is a similar view showing the key segments withdrawn.

Fig. 4 is a detail sectional view of a portion of the structure showing the connections between one of the key segments, and the 20 main segments, and

Fig. 5 is an edge view of a portion of one of the main segments.

This invention relates to an improvement in collapsible cores for molds, and more particularly relates to cores for concrete molds.

The object of my invention is to provide a core which can readily be collapsed and extended, and in which all of the parts are connected to each other. A further object 30 of my invention is to provide a core in which the various members will automatically be collapsed when a single operating member is actuated. A further object of my invention is to provide a core in which the tops 35 and the bottoms of the members can be adjusted relative to each other, and in which all of the members will be moved at an angle to the axis of the mold and at an angle to the line at right angles to the axis 40 of the mold.

The precise nature of my invention will be best understood by reference to the accompanying drawings, which will now be described, it being premised, however, that 45 various changes may be made in the details of construction and the general arrangement of the parts without departing from the spirit and scope of my invention as defined in the appended claims.

Referring to the accompanying drawings, the reference character 2 designates a base board or pallet for supporting the core and molded article, the outer edges of which are arranged to be engaged by the outer sections 55 of the mold, which may be of any approved type, or the type shown in my co-pending

application, Serial No. 194,390, filed October 2, 1917.

Resting on the pallet is a base plate 3, to which is connected four angle braces 4, 60 and connected to each of these angle braces 4 is an angle iron 5. These angle irons 5 are connected to each other at their upper ends by means of a split casting 6 which forms a journal for a nut 7 having an operating wheel 8 connected thereto. Connected to each angle iron and extending radially therefrom are arms 9, each extending parallel with a similar arm connected to an adjacent angle iron. The outer ends of each 65 set are secured to a spacing member 10, having a guide projection 11 at the end thereof. In the construction shown there are eight sets of these radial arms and eight guide 70 projections, which form four sets of guides 180° from each other for guiding the key segments as hereinafter described. The core itself is composed of four main segments 12 and four key segments 13. Each of the key 75 segments 13 is arranged to slide on two guide projections 11 as clearly indicated in Fig. 1, and connected to each of the key segments 13 are links 14 and 15. The links 14 are connected to the key segments near the lower end thereof and are also connected to a slide block 16, guided between the angle 80 bars 5. Each of the links 15 is connected to a key segment 13 near the upper end thereof and a slide block 17 above the slide block 16. This slide block 17 is also arranged to be guided by the angle bars 5. These slide blocks 16 and 17 are connected to each other by means of a rod 18 which is arranged to permit one of the blocks to 85 be adjusted relative to the other to square 90 up the slides of the key segments with relation to the pallet. The rod 18 is provided with a screw 19 which extends up through the nut 7, and the upper end of this screw is provided with an eye 20 which is arranged to be engaged by the hook of a crane or any suitable device to lift the core as hereinafter 95 described. The main segments 12 are provided with two brackets 21 at each vertical edge thereof at points adjacent to the ends 100 of the links 14 and 15. These brackets are provided with a recess having an inclined face 22, and stops 23 and 24. 25 are pins or projections which extend laterally from the key segments 13 into the recesses in the brackets 21, and in this case I have shown 105 these pins as continuations of the pivot pins

110

for the ends of the links 14 and 15, although separate projections may be formed on the key segments. The brackets 21 and pins 25 are so positioned that the pins normally move along the incline 22 which are at the same angle as the guide projections 11, the stops 23 and 24 are arranged to be engaged by the pins 25 to shift the main segments 12 when collapsing or placing the core. Connected to the pallet is an annular centering member 26 which also forms the bottom for the article to be molded, which in this case is a sewer pipe, and which is arranged to center the segments which form the collapsible core. The upper ends of adjacent main segments are connected to each other by adjustable rods 27 which freely pass through openings in brackets 28 on the segments 12 when the core is collapsed, but prevent the movement of these members beyond a predetermined point when the core is extended. The operation of the device is as follows: If it is desired to remove the formed article to a position other than that at which it is formed, the core, together with the formed pipe, can bodily be moved to another point by connecting the chain hook of a crane to the eye 20. As the chain is raised by means of the crane, the pipe will be supported on the pallet which will, in turn be supported by the different segments of the collapsible core which have an undercut engagement with the annular centering member 26. After the device has been moved to the desired point, the hand wheel 8 is operated, which will elevate the screw 19, and which will, in turn, move the slide blocks 16 and 17 upwardly. This upward movement of the slide blocks 16 and 17 will first move the key segments 13 inwardly and upwardly. As soon as the pins 25 engage the stops 24, the further movement of the key segments 13 will draw the main segments 12 inwardly away from the pipe. As soon as the core has been collapsed sufficiently, it can be removed from the pipe by means of the crane. The core is then moved to another pallet, and the base plate 3 is lowered thereon. As soon as the base plate is seated on the pallet, the hand wheel 8 is moved in the reverse direction to extend the core into engagement with the centering member 26. It will readily be understood by those familiar with the art that if it is desired to make a pipe of larger diameter than the one shown, a liner can be placed between the key members and the link connectors. The advantages of my invention result from the provision of a collapsible core having a plurality of segments connected to a supporting frame and actuating mechanism which are so arranged that all of the segments are withdrawn from the molded article by the actuating mechanism, and supported by the frame when withdrawn.

Also from the provision of core having a plurality of main segments and a plurality of key segments connected to each other in such a manner that the key segments will first be operated and which will, in turn, operate the main segments. Another advantage results from the provision and means for moving the segments upwardly away from the pallet when the core is collapsed, together with positive supporting and guiding means for the core segments on the frame.

I claim:

1. A collapsible core for a mold comprising a plurality of main segments, a plurality of key segments and means to move the key segments toward each other and then move the main segments toward each other, substantially as described. 80

2. A collapsible core for a mold comprising a supporting frame, a plurality of key segments, guides on said frame for the key segments, a plurality of main segments, means for moving the key segments relative to each other, and connecting means between the key segments and the main segments for shifting the main segments after the key segments have been moved a predetermined distance, substantially as described. 85 90

3. A collapsible core for a mold comprising a plurality of main segments, a plurality of key segments, means to move the key segments toward and from each other, guiding means for said key segments, and means for moving the main segments after the key segments have been moved a predetermined distance, substantially as described. 95 100

4. A collapsible core for a mold comprising a supporting frame, a plurality of key segments, means on the frame for guiding the key segments, actuating mechanism for moving the key segments relative to each other mounted on said frame, a plurality of main segments, and connections between the key segments and the main segments for actuating the main segments after the key segments have been moved a predetermined distance, substantially as described. 105 110

5. A mold having a supporting frame, a plurality of mold members arranged to move relative to each other, and mechanism for moving the mold members relative to each other, supported on said frame, substantially as described. 115

6. A mold having a supporting frame, a plurality of mold members arranged to move relative to each other, mechanism connected to the frame for moving the mold members relative to each other, and guide members on the frame and some of the mold members for supporting and guiding said mold members when moved away from their molding positions, substantially as described. 125 130

7. A mold having a central supporting frame, two sets of mold members arranged to move relative to each other, guiding supports on the frame for one set of said members, actuating connections for said members, and actuating and supporting members on the first set of members for moving the second sets of members and supporting them during the movement thereof, substantially as described.

8. A mold having a base plate or support, a supporting frame mounted thereon, guide members on said supporting frame, a plurality of mold sections mounted on said guides and arranged to move thereon, actuating members connected to the supporting frame and mold members, said actuating members and guides being arranged to move the mold members toward each other and away from the base of the

mold, other mold sections arranged to move to and from each other, and means for moving the last mentioned mold sections, substantially as described.

9. A concrete mold comprising a pallet, 25 a frame mounted thereon, guides on said frame, a plurality of mold sections mounted on said guides, said guides being arranged to cause the mold sections when moved toward or away from each other to be moved 30 in an angle with relation to the pallet, actuating devices for the mold sections mounted on the frame, other mold sections between the first mentioned mold sections, and means on the first mentioned mold sections for moving and supporting the second mold sections, substantially as described. 35

In testimony whereof, I have hereunto set my hand.

CHARLES F. BUENTE.
